UNITED STATES PATENT OFFICE.

CLARENCE C. NELLIS, OF COLD BROOK, NEW YORK.

RADIATOR CAP.

Application filed December 4, 1922. Serial No. 604,823.

To all whom it may concern:

Be it known that I, CLARENCE C. NELLIS, a citizen of the United States, residing at Cold Brook, in the county of Herkimer, 5 State of New York, have invented certain new and useful Improvements in Radiator Caps; and I do hereby declare the following to be a full, clear, and exact description of the invention, such as will enable others 10 skilled in the art to which it appertains to make and use the same.

This invention relates to new and useful improvements in closures and particularly to closures for the filling tubes of automobile radiators.

The filling tube of the ordinary radiator is so constructed that it is necessary to entirely remove the cap from the filling tube, and then either drop the cap into the pocket 20 of a garment or lay it down somewhere, with the obvious danger of the same being lost or dropping in the dirt, so that the threads will become closed or clogged and carry the deposit into the water within the 25 radiator.

One object of this invention is to provide a cap for a radiator filling tube which does not have to be removed from the tube, but which has a movably mounted portion 30 arranged to be swung open when the radiator is to be filled.

Another object is to provide a cap of this character having a cap arranged to screw into the filling tube and a hingedly mounted cover arranged to be swung upwardly for filling the radiator, and which has means for holding it against accidental opening movement.

A further object is to provide a filling 40 cap of this character having a strainer to prevent the entrance of dust, dirt or other foreign matter with the water when the radiator is being filled.

Other objects and advantages will be apparent from the following description when taken in connection with the accompanying drawing.

In the drawing:

Figure 1 is an elevation of a radiator 50 cap, made in accordance with the invention, and seated within the filling tube of

a radiator, the filling tube being in section.

Figure 2 is a view of the same parts shown in Figure 1, but with the cover swung into open position.

55

Figure 3 is a vertical central sectional view through the cap in a plane parallel to that of Figures 1 and 2.

Referring particularly to the accompanying drawing 10 represents the interiorly threaded filling tube of the radiator 11, in connection with which the present invention is used.

The radiator cap includes a body in the form of a ring 12, having the external 65 threaded portion 13, which is engaged in the filling tube 10. The upper portion of the body is of less diameter than the threaded portion, and has a smooth exterior 14.

At one point in this smooth faced portion 70 14 there is a notch 15, and secured within this notch is a hinge 16. Connected to this hinge is the smooth-faced flange 17' of the cover 17, which flange is of slightly greater diameter than the portion 14 and arranged 75 to snugly embrace this latter portion when brought down thereon. The cover portion 17 has a hand hold 18 which is grasped to unscrew the device from the filling tube, when it is desired to remove the same from 80 the filling tube. In the outer face of the portion 14, diametrically opposite to the hinge, there is formed a small boss 18' which is arranged to snap into a recess 19, formed in the inner face of the flange 17', to hold 85 the outer part against accidental opening movement. When the cap is properly screwed down into the filling tube this cover 17 will lie above the upper end of the body 12 of the cap so that said cover may be 90 swung open, when desired but which is held from accidental opening by the boss 18'.

A screen 19 is secured across the lower end of the tube so as to prevent the entrance of dust, dirt or other foreign substances 95 which might pass in with the water when the radiator is being filled.

What is claimed is:

The combination with the internally threaded filling tube of an automobile radiator, of a closure therefor including a tube 100 having its intermediate portion exteriorly

threaded for engagement within the filling tube and its end portions externally smooth, the smooth portion of the closure tube within the filling tube being tapered and terminally carrying a strainer, and a cap hinged to the inner end of the outer smooth portion of the closure tube and enclosing said portion when in closed position, said hinged portion of the cap and tube serving to limit

the inward movement of the tube within 10 the filling tube.

In testimony whereof, I affix my signature, in the presence of two witnesses.

CLARENCE C. NELLIS.

Witnesses:

CORA L. NELLIS,
MILDRED WAGNER.
